UNITED STATES PATENT OFFICE.

MARTIN THUM, OF ROCHESTER, NEW YORK, ASSIGNOR TO STRATTON C. LANGSLOW,
OF ROCHESTER, NEW YORK.

RECLINING-CHAIR.

1,279,943.

Specification of Letters Patent. Patented Sept. 24, 1918.

Application filed April 14, 1913. Serial No. 760,946.

To all whom it may concern:

Be it known that I, MARTIN THUM, of Rochester, of the county of Monroe and State of New York, have invented certain new and useful Improvements in Reclining-Chairs; and I do hereby declare the following to be a full, clear, and exact description of the same, reference being had to the accompanying drawings, forming a part of this specification, and to the reference-numerals marked thereon.

My invention has for its object to provide a novel construction and arrangement of elements in reclining chairs of the general type involving a movable seat and back connected together for simultaneous and corresponding movements, whereby the rear portion of the seat is elevated in proportion as the back is inclined to the perpendicular. A further purpose of my invention consists in providing a simple and readily operated mechanism so that a person while sitting in the chair can easily control and change the positions of the back and seat, and thus adjust the chair to any position. Another object of my invention resides in the provision of a construction that will give strength and rigidity to the movable parts of the chair, and at the same time enable them to be held fixedly in any desired position of adjustment. To these and other ends the invention consists in certain improvements and combinations of parts, all as will be hereinafter more fully described, the novel features being pointed out in the claims at the end of the specification.

In the drawings:

Figure 1 is a view in side elevation, with parts broken away, showing a preferred embodiment of my improvements;

Fig. 2 is a plan view of the rear part of the base frame;

Fig. 3 is an enlarged view in elevation of the adjusting mechanism employed to change the positions of the back and seat, and

Fig. 4 is a sectional view on the line 4—4 of Fig. 2.

Similar reference numerals throughout the several figures indicate the same parts.

In the present embodiment of the invention, 1 designates the sides of the base frame of the chair, which is further provided with arms 2, front legs 3 and back legs 4 between which is arranged a cross piece 5. 6 is the

seat frame loosely supported at the front on the base frame, and which is supported at the rear in a manner that will presently be described. 7 is the back frame, to the sides of which are attached the link members 8 which are provided with rear slots 9 in their lower edges and front slots 10 in their upper edges in the manner shown in Fig. 1, and for a purpose that will now appear. 11 designates a support, in the form of a rod, which is attached between the back legs 4 of the base frame and which serves to hold the back frame in position, the latter being held thereon by the engagement of the rear slots 9. The seat frame is maintained in proper relation to the back frame by being connected therewith, and to this end is provided with pins or projections 12 which engage in the front slots 10 of the link members 8. By this arrangement, it will be seen that as the back frame is moved rearwardly, as illustrated in dotted lines in Fig. 1, the link members 8, connecting with the seat frame, effect an upward movement of the latter, causing it to assume a corresponding position, as shown in dotted lines. In order to effect the adjustment as indicated, and to hold the parts in the desired position, I provide the following mechanism:

Secured between the cross piece 5 and the cross piece 13, which is arranged between the front and rear of the base frame, is a guide 14 preferably disposed at an angle to the horizontal as shown, said guide being provided with a longitudinally extending slot or opening 15 which receives the holder that will now be described and permits adjustment of the latter to different parts of the guide. The holder comprises an upper plate 16 engaging the upper face of the guide, and a lower plate which is attached to the upper plate and has a central reduced portion 17 engaging the slot 15, and offset lateral extensions 18 engaging the under face of the guide. The holder is provided at one edge with a series of teeth 19, preferably formed in the edge of the upper plate 16 and arranged to be engaged by a suitable locking member. The locking member preferably consists of a rack bar 20 which has a right angled flange 21 and end flanges 22 by which it is pivotally mounted on the ears 23 of the guide, so as to swing on a longitudinal axis, in order to bring the rack bar into and out of engagement with the teeth 110

19 of the holder. The locking member is actuated and held in normal locking position in any suitable manner, a convenient means to this end consisting in the following mechanism. 24 is a lever mounted on the rock shaft 25, and arranged immediately beneath the arm of the chair so as to be conveniently accessible. The rock shaft 25 is provided at its lower end with an angle arm 26 from 5 which a connecting rod 27 leads to an arm 28, the latter being fixed upon the locking member in the manner shown, and connected to the rod 27 by means of the cotter-pin 29. 30 is a spring also connected to the 10 arm 28 and having its opposite end secured to the base frame of the chair so as to retain the locking member normally in engagement with the holder. When it is desired to change the position of the back and seat, the 15 lever 24 is operated, to release the holder and permit it to slide along the guide 14 until the desired position is obtained. The back frame is connected to the holder in any suitable manner so as to control the movement 20 of the seat and back, and to hold them in adjusted positions, and to this end I preferably provide a connecting member in the form of a rod 31 which is disposed centrally 25 of the back frame and extends downwardly through an elongated opening 32 in the holder. By this construction it is possible to readily and accurately adjust the back of 30 the chair, and correspondingly the seat, to any position, by a slight pressure of the body, this operation being permitted when 35 the lever 24 is moved to unlock the holder; and immediately on releasing the lever, the locking member is actuated by the spring 30 to engage the holder and retain the parts 40 in such position. The elongated opening in the holder permits the connecting member 31 to move with the holder to any point of the slot in the guide freely, and without any binding action between the connected 45 parts. The holder also serves to prevent the accidental displacement of the back frame upon the pivots 11 when the seat frame is removed from the back frame. At the same time the locking mechanism for the back 50 frame may be operated to adjust said frame regardless of the removal of the seat frame.

While I have disclosed a particular embodiment of my invention, it should be understood that I am not limited to the exact 55 construction herein described, for I may employ various other arrangements and modifications without departing from the essential features of my improvements as covered by the claims hereinafter.

60 I claim as my invention:

1. In combination with the base frame of a chair, a seat frame and back frame pivotally mounted on the base frame and pivotally connected for obtaining corresponding movements; a stationary guide on

the base frame, an adjustable holder movable on the guide independently of the movement of the seat frame, means for locking the holder on the guide, and a connecting device carried by the back frame and in engagement with said holder. 70

2. In combination with the base frame of a chair, a seat frame and back frame pivotally mounted on the base frame and pivotally connected for obtaining corresponding movements, a stationary guide arranged centrally on the base frame, an adjustable holder slidable on the guide independently of the seat frame, means for locking the holder on the guide, and a connecting device disposed centrally of the back frame and in engagement with said holder. 75 80

3. In combination with the base frame of a chair, a seat frame and back frame pivotally mounted on the base frame and pivotally connected for obtaining corresponding movements, a stationary guide on the base frame, an adjustable holder movable on the guide independently of the seat frame and having an opening therein, means for locking the holder on the guide, and a rod carried by the back frame and in engagement with said opening in the holder. 85 90

4. In combination with the base frame of a chair, a seat frame and back frame pivotally mounted on the base frame and pivotally connected for obtaining corresponding movements, a stationary guide on the base frame, an adjustable holder movable on the guide independently of the seat frame, a locking member pivotally mounted to engage and disengage the holder, means for actuating the locking member, and a connecting device disposed on the back frame and in engagement with the holder. 95 100

5. In combination with the base frame of a chair, a seat frame and back frame pivotally mounted on the base frame and pivotally connected for obtaining corresponding movements, a stationary guide on the base frame, an adjustable holder slidable on the guide independently of the seat frame and having a series of teeth on one edge, a pivoted locking bar adapted to engage and disengage said teeth, means for actuating the locking bar, and a connecting device disposed on the back frame and in engagement with the holder. 110 115

6. In combination with the base frame of a chair, a seat frame and back frame pivotally mounted on the base frame and pivotally connected to each other for obtaining corresponding movements, a stationary guide on the base frame, an adjustable holder slidable on the guide independently of the seat frame and having a series of teeth on one edge, a locking bar mounted to swing about a longitudinal axis to engage and disengage said teeth, a lever at the side of the base frame, connections between the lever 120 125 130

and said locking bar, and a connecting device disposed on the back frame and in engagement with the holder.

7. In combination with the base frame 5 of a chair, a seat frame and back frame pivotally mounted on the base frame and pivotally connected for obtaining corresponding movements, a stationary guide on the base frame, an adjustable holder slid- 10 able on the guide independently of the seat frame having a series of teeth on one edge, a locking rack bar pivotally mounted on a

longitudinal axis to engage and disengage said teeth on the holder, means for normally holding the bar in locking engagement, 15 means for actuating the locking bar to release the same, and a connecting device disposed on the back frame and in engagement with the holder.
